UNITED STATES PATENT OFFICE.

JOHN STUART, OF ST. KILDA, MELBOURNE, VICTORIA, AUSTRALIA.

RESILIENT WHEEL.

1,266,343.

Specification of Letters Patent. Patented May 14, 1918.

Application filed December 3, 1917. Serial No. 205,176.

To all whom it may concern:

Be it known that I, JOHN STUART, a subject of the King of Great Britain and Ireland, and a resident of the city of St. Kilda, a suburb of the city of Melbourne, in the county of Bourke, State of Victoria, Commonwealth of Australia, and whose post-office address is 19 Addison street, in the said city of St. Kilda, have invented a certain new and useful Improved Resilient Wheel, of which the following is a specification.

This invention relates to improvements in resilient vehicle wheels and its object is to provide a simple and efficient structure which may be easily and quickly assembled or dismantled and is adapted for use with either pneumatic, cushion, or solid tires.

Referring to the drawings which form a part of this specification—

Fig. 1 is a view looking at the outer side of the wheel. In the right hand half of the figure the outer circular side plate is removed to show clearly the disposition of the segmental cushions.

Fig. 2 is a cross section of the wheel taken through the segmental cushions. The outer side plate is shown detached for convenience of illustration.

Fig. 3 is a perspective view of a segmental cushion.

Fig. 4 is a sectional detail view of a modification in which the ends of the cushions and the cavities which accommodate them are of dovetail conformation.

Fig. 5 is a sectional detail view of a further modification in which the ends of the cushions are convex and the ends of the cavities concave.

Fig. 6 is a fragmentary cross section on an enlarged scale taken through one of the cushions. The outer side plate is shown in position and the tire is removed.

Fig. 7 is a cross section taken between two of the cushions.

Fig. 8 is a detail view looking at the inside of the outer removable side plate and showing the inclined edges of the blocks or abutments which fit within the cavities of the inner rim.

Fig. 9 is a perspective view of portion of the outer side plate.

Fig. 10 is a perspective view of portion of the inner rim showing clearly the conformation of the cavities therein.

The invention includes a hub element which may be of any suitable material wood being preferred. The hub element comprises a hub 2 from which radiate spokes 3 attached at their outer end to an inner rim 4. This inner rim is surrounded by a metallic ring 6 which securely retains the parts of the hub element together.

Formed in the periphery of the inner rim and the metallic ring 6 are a series of segmental cavities the end walls 7 of which are preferably of convex form as shown. These cavities are open on the outer side of the wheel but on the inner side are closed by an inner wall 8 which coincides with a bridge 9 formed in the metallic ring 6 where it is cut away to form the cavities. The open outer side of each cavity in the inner rim is preferably provided with an inclined bottom edge 11 and inclined side edges 12 as shown, the object of these inclined edges being to facilitate the insertion of the cushions as will be hereinafter better understood.

Surrounding the hub element is a felly 13 the inner diameter of which is greater than the outer diameter of the inner rim 4. Accordingly an annular space 14 exists between the felly and the hub element. Formed through the felly are a series of segmental cavities the end walls 16 of which are preferably convex and when the wheel is assembled are in alinement with the convex ends 7 of the cavities in the inner rim. The cavities in the felly are closed on both sides of the wheel by an inner wall 17 and an outer wall 18. To the outer circumference of the felly is attached by screws 19 or the like an outer rim 21 which may be designed to carry either a solid, cushion, or a pneumatic tire 22 as desired. When a pneumatic tire is used the valve 20 passes freely through an opening formed in one of the cushions for this purpose.

Accommodated by corresponding cavities in the inner rim and the felly are a series of segmental cushions 23. These cushions are preferably of rubber and are provided with concave ends which fit tightly against the convex end walls of the cavities. The cushions are preferably formed of a series of circumferential laminations 24 which are incorporated into a single block as in Fig. 3 by any well known means. Before insertion the cushions are actually larger than the cavities which accommodate them, the cushion

ions being forced into said cavities under pressure by any suitable means so that when in use they are comparatively hard and under ordinary load support the hub element substantially concentrically within the felly. Only on encountering road inequalities do the cushions become compressed and the felly and hub radially displaced in relation to each other. This feature contributes largely to the efficiency of the wheel.

Instead of the cushions having concave ends as shown in Figs. 1 and 3 they may be of dovetail shape as at 25 in Fig. 4, the cavities being similarly shaped to accommodate them. The shape of the ends may be still further modified as seen in Fig. 5 which illustrates a cushion having convex ends 30 fitting within cavities of concave form.

Attached to the inner side of the wheel is an inner circular side plate 26 which extends around the felly and the inner rim covering the annular space existing therebetween and forming guides for the felly. The inner side plate is preferably fixed to the inner rim by screws 27 or the like but it may be detachable and held in place by means of a series of bolts 28 which pass through bolt holes in the inner rim.

Attached to the outer side of the wheel by means of the bolt 28 is an outer circular side plate 29 which may be removed by unscrewing the nuts 31 and from its inner face protrude a series of blocks or abutments 32. These blocks are accommodated by the open side of the cavities in the inner rim and fit against the cushions and prevent any lateral displacement thereof. Each of the blocks or abutments is preferably provided with an inclined bottom 33 and inclined sides 34 which fit against the inclined edges 11-12 of the cavities in the inner rim.

In assembling the wheel the cushions are forced under pressure into the cavities of the felly so that the concave ends of the cushions fit tightly against the convex end walls of the cavities and are thus held securely in place. The felly is then placed concentrically around the hub element, so that the cushions register with the cavities of the inner rim. The felly is then forced over the hub element, the inner portion of the cushions entering the cavities in the inner rim through the inclined openings in the outer side thereof until they engage the inner wall 8 and are tightly held in place by the convex ends of the cavities. The outer side plate is then placed in position so that the blocks or abutments fill the cavities in the inner rim and engage the outer sides of the cushions. The tightening up of the nuts 31 on the bolts 28 secures the outer side plate in place and the wheel is ready for use.

To obtain access to the cushions for inspection, renewal or repair, or for the pur-

pose of dismantling the wheel it is only necessary to remove the nuts 31 whereupon the outer side plate may be withdrawn.

By the construction above described a simple and compact wheel is provided which is extremely strong and highly efficient and permits of a greater degree of unsprung weight in the chassis of the vehicle. As will be seen the segmental cushions form resilient bridges between the felly and the hub element which nullify the effect of road shocks without fear of dislocation or derangement of the parts.

Having described my invention I claim:—

1. In a resilient wheel, the combination with a hub element including an inner rim, said inner rim having a plurality of radial cavities which are transversely tapered at their ends with the ends diverging inwardly with respect to the hub element, said cavities having their inner sides closed and their outer sides open; of a felly surrounding and spaced from the inner rim, said felly having cavities corresponding in arrangement to the first named cavities, the second named cavities being radially disposed and having their ends tapered and diverging outwardly with relation to the hub element, said second named cavities having both sides closed; a plurality of cushions having their opposite ends inclined inwardly from their opposite longitudinal edges, and adapted for insertion within the first and second named cavities; and means adapted for insertion through the open sides of the first named cavities to contact with said cushions and retain the same in place.

2. In a resilient wheel the combination of a hub element having an inner rim in which are a series of segmental cavities open on the outer side of the wheel and inclosed on the inner side thereof, a felly surrounding and spaced from the hub element said felly having cavities corresponding in arrangement to the cavities of the inner rim and having both sides closed, a series of segmental cushions accommodated by said cavities and extending between the inner rim and the felly, an inner circular side plate covering the space between the inner rim and the felly on one side of the wheel, an outer removable side plate covering said space on the outer side of the wheel and abutments protruding from said outer side plate and accommodated by the open side of the cavities in the inner rim.

3. In a resilient wheel, the combination of a hub element having an inner rim in which are a series of segmental cavities open on the outer side of the wheel and having convex end walls, a felly surrounding and spaced from the hub element, said felly having cavities with convex ends which are arranged in alignment with the ends of the cavities in the inner rim, a series of seg-

mental cushions extending between the inner rim and the felly and having concave ends engaging the ends of the cavities therein, an inner fixed side plate covering the 5 space between the inner rim and the felly on one side of the wheel, an outer removable side plate covering said space on the outer side of the wheel, and abutments protruding inwardly from the outer side plate and 10 accommodated by the open side of the cavities in the inner rim, said abutments engaging the outer side of the cushions.

4. In a resilient wheel the combination of a hub element having an inner rim in which 15 are a series of segmental cavities open on the outer side of the wheel, a felly surrounding and spaced from the hub element said felly having cavities arranged in alinement with the cavities of the inner rim, a series 20 of segmental cushions accommodated by said cavities and extending between the inner rim and the felly, an inner circular side plate covering the space between the inner rim and the felly on one side of the wheel, 25 an outer removable side plate covering said space on the outer side of the wheel, abutments protruding from the outer side plate and accommodated by the open side of the cavities in the inner rim, said cavities in 30 the inner rim having inclined outer edges to facilitate the introduction of the cushions and said abutments having inclined ends and an inclined bottom to engage the inclined edges of said cavities.

5. In a resilient wheel, the combination of a hub element having an inner rim in which are a series of segmental cavities open on the outer side of the wheel and having convex end walls, a metallic ring surrounding and attached to said rim, a felly surrounding and spaced from the hub element, said felly having cavities with convex ends which are arranged in alinement with the cavities of the inner rim, a series of segmental cushions having concave ends engaging the convex ends of the cavities, said 45 cushions extending between the inner rim and the felly, an inner circular side plate attached to the inner rim and covering the 50 space between the inner rim and the felly

on one side of the wheel, an outer removable side plate covering said space on the outer side of the wheel, and abutments carried by said outer side plate and accommodated by the open side of the cavities in the inner 55 rim, said abutments having inclined edges which engage corresponding edges in the cavities of the inner rim.

6. In a resilient wheel the combination of a hub element having an inner rim in 60 which are a series of segmental cavities, a felly surrounding and spaced from the hub element, said felly having cavities corresponding to the cavities of the inner rim, a series of circumferentially laminated cushions compressed into said cavities and extending between the inner rim and the felly, an inner circular side plate covering the space between the inner rim and the felly 65 on one side of the wheel, an outer removable side plate covering said space on the outer side of the wheel, a metallic ring surrounding and attached to said inner rim, said metallic ring having narrow bridges opposite each of the cavities in the inner rim. 70

7. In a resilient wheel the combination of a hub element having an inner rim in which are a series of segmental cavities, a metallic ring surrounding and attached to said inner rim and having cavities corresponding with 80 those in the inner rim, said cavities being open on the outer side of the wheel and closed on the inner side thereof by an inner wall, a felly surrounding the inner rim and spaced therefrom, said felly having cavities 85 closed on both sides of the wheel, segmental cushions extending between the inner rim and the felly and accommodated by the cavities therein, an outer rim attached to the periphery of the felly, a tire carried by the 90 outer rim, an inner side plate secured to the inner side of the inner rim and an outer side plate removably attached to the outer side of the wheel said outer side plate having abutments accommodated by the open side 95 of the cavities of the inner rim and engaging the cushions therein.

In testimony whereof I affix my signature.

JOHN STUART.
